Primary Examiner — Selina Sikder

(74) Attorney, Agent, or Firm — Gerald E. Hespis;
Michael J. Porco; Matthew T. Hespis(57) **CLAIM**

The ornamental design for a front panel soft starter, as shown and described.

DESCRIPTION

The sole FIGURE is a front elevation view of the front panel soft starter showing my new design wherein all features shown are in a single plane and perpendicular to the line of sight.

The broken lines illustrate portions of the front panel soft starter that do not form part of the claimed design.
